(57) **CLAIM**

The ornamental design for an earphone clip, as shown and described.

DESCRIPTION

FIG. 1 is a perspective view of an earphone clip, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is another perspective view thereof, shown in an environment of use.

The different shading patterns represent a contrast in appearance. The broken lines shown in FIGS. 4-6 illustrate portions of the earphone clip that form no part of the claimed design. The broken lines shown in FIG. 8 illustrate environment that forms no part of the claimed design.
